UNITED STATES PATENT OFFICE.

EDWARD N. JACOBI, OF MILWAUKEE, WISCONSIN, ASSIGNOR TO BRIGGS AND STRATTON CORPORATION, OF MILWAUKEE, WISCONSIN, A CORPORATION OF DELAWARE.

LOCK.

Application filed January 6, 1928. Serial No. 244,891.

This invention has for an object the provision of an improved tumbler lock having means embodied therein whereby a smooth cam action is provided between the cylinder 5 tail or cam and the locking bolt to reduce friction and insure the easy actuation of the lock.

Another object of this invention resides in the provision of an improved lock structure 10 of the character described having a rod or lever member disposed between the cylinder carried cam or tail and the locking bolt or pin to produce a leverage on the locking bolt and increase the mechanical advantage of 15 the force applied thereto by the cylinder cam or tail and insure a smoother operation of the lock.

A further object of this invention resides in the provision of an improved lock of the 20 character described in which the locking bolt is at all times normally rotated to its locked position.

And a still further object of this invention 25 is to provide an improved manner of assembling the lock.

With the above and other objects in view which will appear as the description proceeds, my invention resides in the novel construction, combination and arrangement of 30 parts substantially as hereinafter described and more particularly defined by the appended claims, it being understood that such changes in the precise embodiment of the herein disclosed invention may be made as 35 come within the scope of the claims.

In the accompanying drawing, I have illustrated one complete example of the physical embodiment of my invention constructed according to the best mode I have 40 so far devised for the practical application of the principles thereof, and in which:

Figure 1 is a view, partly in longitudinal section and partly in elevation, of a lock embodying my invention;

Figure 2 is a view, partly in section and partly in elevation, taken through Figure 1 on the plane of the line 2-2; and

Figure 3 is a fragmentary, perspective detail view of the inner end of the lock cylinder and lever detached from the cylinder mounting head and illustrating the locking bolt in phantom.

Referring now more particularly to the accompanying drawing, in which like numerals designate like parts throughout the

several views, 5 designates a lock cylinder mounting head having a central bore 6 extended throughout the major portion of its length and closed at its inner end by a wall 7. A transverse bore 8 is located at 60 the inner end of the bore 6 and intersects its axis, the bore 8 communicating with the periphery of the mounting head 5 at one end to permit the projection therebeyond of the end 9 of the locking pin or bolt 10 reciprocally mounted within the bore 8.

The bolt 10 is of cylindrical form having its medial portion milled or otherwise cut out, as at 11, and its inner end 12 counter-bored to receive one end of a spring 13, the 70 other ends of which abuts the closed end 14 of bore 8 to normally urge the end 9 of the locking bolt beyond the periphery of the head 5.

A lock cylinder 15 of conventional construction is rotatable within the bore 6 and carries suitable tumblers 16 which are normally spring urged to engage within one of two longitudinal slots 17 in the wall of the bore 6, the tumblers being retracted within 80 the plane of the cylinder periphery upon insertion of a proper key 18 in the conventional slot of the cylinder. The outer end 19 of the cylinder 15 extends beyond the outer end of head 5 and fits within a sealing 85 cap 20 which is connected therewith for rotation by a projection or lug 21 on the outer end of the cylinder which engages in one end of the cap key slot or opening 22 which aligns with the key-receiving opening 90 of the cylinder. The cap 20 has an annular flange or shoulder 23 over which the instruck annular flange or rib 24 of a casing 25 engages, the inner end of the casing being laterally flanged, as at 26, and fitted within 95 a counterbore 27 at the base of the outer reduced portion 28 of the head 5 and there secured by spinning or crimping the material thereover, as at 29. In this manner the lock mechanism is assembled and a neat 100 and strong structure provided.

A two step cam or tail piece 30 is formed on the inner end of the cylinder 15, the first step 31 having an external diameter substantially concentric with that of the cylinder 105 proper but of a similar radius and preferably extending throughout more than 180 degrees and with its inside shape forming substantially an L. The second step 32 has the same external diameter as the first step but its 110

ends terminate short of the ends of the first step, the end 33 thereof being spaced a greater distance from the adjacent end of the first step than its end 34 is spaced from 5 its adjacent first step end, for the reason later described.

The cam 30 extends into the milled or cut away portion of the locking bolt 10 and in conventional constructions, the end or 10 shoulder 35 of the cam engages the wall 36 of the locking bolt cut away portion so, that upon rotation of the cylinder in a counter-clockwise direction with respect to Figure 2, it cams thereagainst to retract the locking 15 bolt against its spring 13. With the cam engaging directly on the wall 36 of the locking bolt, the friction between the parts interferes with the free movement of the locking bolt by its spring when the pressure on the key 20 18 is released.

In the present invention, a lever member 37 of approximately L shape is mounted within the bore 6 with the vertical portion of the L interposed between the cam 30 and the locking bolt shoulder or wall 36, the 25 horizontal or short arm 38 of the lever being pivoted in an aperture or well 39 in the end wall 7 of the mounting head and the long arm of the L passing through the cut away 30 portion of the locking bolt with its extreme outer end directed or bent laterally, as at 40, to normally rest on the surface or shoulder 41 formed between the ends 34 and 35 of the cam steps. The bend 42 at the outer end of 35 the long arm of the L forms a fulcrum point engaging the shoulder 36 of the locking bolt and the bend 43 forms a fulcrum point engaging the end 34 of the cam step 32.

The lever 37 eliminates rubbing of the cam 40 across the face 36 of the bolt and the curved surfaces 42 and 43 of the lever are so formed that the pressure at the points of contact are substantially normal to those surfaces in the direction that will most effectively rotate the cylinder and slide the bolt, respectively, thus 45 diminishing friction between the parts. The long end 31 of the first cam step at all times extends over the lever 37 to prevent its disengagement from the aperture 39 and to 50 prevent the end of the lever within the milled slot of the bolt 10 from riding over the shoulder 36 should the bolt rotate in its bore.

From the foregoing description, taken in connection with the accompanying drawing, 55 it will be readily evident to those skilled in the art to which an invention of the character described pertains, that I have provided a novel and improved lock assembly whereby friction between the cylinder and the locking bolt is reduced to a minimum and the return of the bolt and cylinder to normal locking position at all times is assured, and further that a better manner of securing the assembly within the mounting head is obtained. 60

What I claim as my invention is:

1. In a lock, a mounting head, a key controlled cylinder rotatable within the mounting head, a cam projection on the inner end of the cylinder, a locking bolt slidable in the mounting head and having a shoulder, and a lever member having a portion transversely interposed between the cam projection and said locking bolt shoulder whereby rotation of the cylinder actuates the locking bolt. 75

2. In a lock, a mounting head, a key controlled cylinder rotatable within the mounting head, a cam projection on the inner end of the cylinder, a locking bolt slidable in the mounting head and having a shoulder, a lever member, and means pivotally mounting one end of said lever member, the free end of the lever member being interposed between the cam projection and the locking bolt whereby rotation of the cylinder actuates the locking bolt. 85

3. In a lock, a mounting head, a key controlled cylinder rotatable within the mounting head, a two step cam projection on the inner end of the cylinder, the ends of the second step of the cam terminating inwardly of the adjacent ends of the first step of the cam, a locking bolt slidable in the mounting head adjacent the inner end of the cylinder and having a medial cut away portion into which the cylinder cam projection extends, and a pivoted lever member having its free end disposed between one end of the cam and one end wall of the bolt cut away portion. 90

4. In a lock, a mounting head, a key controlled cylinder rotatable within the mounting head, a projection on the inner end of the cylinder, a spring pressed locking bolt slidable in the mounting head adjacent the inner end of the cylinder and having a medial cut away portion into which the cylinder cam projection extends, and a pivoted lever member of substantially L 105 shape and having one arm pivoted in an opening in the mounting head and its other arm interposed between the cam projection and one wall of said locking bolt cut away portion. 110

5. In a lock, a mounting head, a key controlled cylinder rotatable within the mounting head, a two step cam projection on the inner end of the cylinder, the ends of the second step of the cam terminating inwardly of the adjacent ends of the first step of the cam, a spring pressed locking bolt slidable in the mounting head adjacent the inner end of the cylinder and having a medial cut away portion into which the cylinder cam projection extends, and a pivoted lever member of substantially L shape and having one arm pivoted in an opening in the mounting head and its other arm interposed between 120 125 130

one end of the second step of the cam projection and one wall of the bolt cut away portion.

6. In a lock, a mounting head, a key controlled cylinder rotatable within the mounting head, a two step cam projection on the inner end of the cylinder, the ends of the second step of the cam terminating inwardly of the adjacent ends of the first step of the cam, a spring pressed locking bolt slidable in the mounting head adjacent the inner end of the cylinder and having a medial cut away portion into which the cylinder cam pro-

jection extends, and a pivoted lever member of substantially L shape and having one arm pivoted in an opening in the mounting head and its other arm interposed between one end of the second step of the cam projection and one wall of the bolt cut away portion, the outer end portion of said lever having opposed bends engaging the cam projection and the adjacent wall of the locking bolt cut away portion. 15

In testimony whereof, I hereunto affix my signature.

EDWARD N. JACOBI.
